G. H. Sellers.

Making Eye-Bolts or Links.

N° 82559

Patented Sept. 29, 1868.

United States Patent Office.

GEORGE H SELLERS, OF PHÆNIXVILLE, PENNSYLVANIA.

Letters Patent No. 82,559, dated September 29, 1868.

IMPROVED METHOD OF MAKING EYE-BOLTS OR LINKS WITHOUT WELDING.

The Schedule referred to in these Letters Patent and making part of the same.

TO ALL WHOM IT MAY CONCERN:

Be it known that I, GEORGE H. SELLERS, of Phoenixville, in the county of Chester, and State of Pennsylvania, have invented certain new and useful Improvements in Machines for Making Weldless Links, &c., from Rolled Bars of Iron; and I do hereby declare the following to be a full, clear, and exact description of the same, reference being had to the accompanying drawings, making a part of this specification, in which—

Figure 1 represents a top plan of the machine.

Figure 2 represents a side elevation of the same.

Figure 3 represents an end elevation.

Figure 4 represents a vertical section through a pair of flattening-dies, and showing how a flat eye, and a hole in the same, are formed on a flat bar.

Figure 5 represents a top plan of the flattening-dies.

Figure 6 represents a pair of dies for forming the ball or stock from which the eye is made on round bars.

Figure 7 represents an elevation of said dies.

Figure 8 represents an end elevation of the said dies.

Figure 9 represents a side elevation of the male die or flattener, used in forming the eye and hole in the same on a round bar.

Figure 10 represents a plan of the female die, used with the male die represented in fig. 9.

Figure 11 represents a vertical section of the dies or flatteners used in making a flat eye, and a hole in the same, on round bars.

Similar letters of reference, where they occur in the separate figures, denote like parts of the machine in all of the drawings.

The methods heretofore essayed for making weldless links and similar articles from bars of rolled iron, by swaging or upsetting, enlarging, and shaping in dies, have failed of complete success, by attempting too much, viz, by trying to force the iron at once into the form it was designed to ultimately have. In attempting this, a practical difficulty occurs, caused by the excessive friction of the particles of metal upsetting upon the dies or formers, which hold it in place, and which prevents the iron from receiving its required shape, as it becomes too cold for the power applied to overcome this friction, and it fails to fill the dies.

The plan which I adopt overcomes the above-mentioned difficulties, as I first form my bar into a shape more easily acquired than the finished shape it has to take. This shape, in all cases, would be the natural form that iron would take if force were applied against the end of it while hot; in other words, I always, in the first process I put the bar through, allow it to swell out radially from the centre of the bar, and thus form upon it a circular or elliptical swell or enlargement. The iron is then again reheated, and placed in a second pair of dies, where this radially forcing out of the metal is continued, and the final form given to the flat end or eye.

And my invention consists in making weldless links, and other similar articles, by first forcing the end of the bar up into a circular, elliptical, or spherical form, in suitably-shaped dies, and then subjecting the previously-swelled-up or enlarged end of the bar to the flattening and bulb-dies, for the purpose of transposing the metal from the place where the bolt-hole is to be made, and driving it towards the perimeter, so as to insure the filling of the dies.

To enable others skilled in the art to make and use my invention, I will proceed to describe the same, with reference to the accompanying drawings.

A, fig. 1, represents a bed, upon which two semi-dies or formers, B B, are pivoted, as at C C, so that they may be swung open and shut, as may be required. The formers are further supported by straps of steel or other metal, D, bolted together by bolts, E, which bolts serve also as pivots or shafts for the lever-cams F to turn upon, said cams being for the purpose of rigidly holding the two parts B B together, and against the resistance of the ram or follower G, when it is driven with force against the end of the bar on which the swell or enlargement is to be made. Within the parts or sections B is formed the die, which is to give the shape, form, and size of the enlargement to be made on the bar. The bar H, in this case, is a flat bar, and is intro-

duced between the shears or sections B, and the latter closed and rigidly clamped by the cam-levers F. The header, ram, or follower G, is then driven with great force against the end of the bar, which, of course, had been previously heated, and the metal driven into all portions of the die, filling the die full, as it has no other means of spreading. From these dies, the bar, with the swell or enlargement upon it, is removed, reheated, and laid into the flattening-dies I J, in each of which there is a rounded, swelled portion at its centre, as at a a, and when the upper die I is brought down upon the bed-die J, or both brought together, these rounded, swelled portions a a force the metal from the part where the eye is to be bored out, and drive it out radially, thus not only insuring of the driving of the metal into the moulds, but working the metal around the eye, and giving it strength where it is most required.

If the eye is to be formed upon a round bar, as that at K, fig. 6, then a spherical or elliptical head or swell is first made upon it, it being clamped in dies or formers, B B, as above mentioned, and operated upon by the follower, header, or ram G, as in the case of the flat bar, but the shape of the dies made different, and to give the proper shape to the swell or stock at the end of the bar. When this is done, the bar is removed, again heated, and the rounded or other-shaped head laid upon the flattening-die J, and the other die, I, is brought down upon it, which flattens out this rounded or other-shaped portion. These dies, I J, like those above described, have also the central projecting rounded portions a a, for the purpose of driving the metal from the centre (where the eye is to be drilled, bored, or punched,) towards the circumference, insuring the filling of the dies, giving the bolt the exact form of the die, and improving the quality of the metal around the eye, where the greatest or most immediate strain comes upon the bar, and, moreover, saves much of the metal hitherto wasted by boring, punching, or drilling, as, by my plan, it is transferred to another place, not removed.

In addition to the cross-bars D, for strengthening the dies against the force or pressure of the follower, other cross-bars, L, may be used at the opposite ends of the dies, and secured to the bolts C C. The cams F turn on the bolts E as a centre, and levers M are connected with the cams, to operate them by.

When a link or enlarged end is to be formed on a flat bar, as that shown at H, the bar, being first heated, is put into the dies, and tightly gripped therein back of the point or place where the enlargement is to be made, and sufficient of the bar must pass through the die, and beyond it, to form the swell or enlargement, or to fill the die, or nearly so, when power is applied to the follower. The dotted lines in figs. 1 and 2, show the form and shape of an enlargement, which is much used, and illustrates the process, these dotted lines representing the cavity in the dies which is to be filled by the upset metal. The bar being thus placed in the dies, the follower or ram G is brought against the end of the bar that is within the die, and the metal is forced out into the cavity, and nearly if not quite filling it, and taking a form approximating that which the swell or enlargement is to have when finished. This being done, the bar is removed and reheated, and laid in the flattening-die J, and the male die I is brought down with great force upon the previously and partially-wrought part, the projections a a, upon the faces of these flattening-dies, forcing the metal out of the centre of the flattened portion which forms the part where the eye of the link is to be. This process, it will be observed, forces the metal radially from the centre, and removes it from where the eye of the bar is to be, and puts more work upon the metal surrounding the eye, improving its quality, and adding much to the strength of the metal at a point or part of its greatest endurance.

The operation upon a round bar does not differ from that just above described on the flat bar. The cavity in the dies is different, of course, but the bar is heated, placed, and gripped in the same way, the follower or ram forced down or in, in the same way, but the swell, instead of being flat or oval in form, is round or spherical. The metal is forced out into this round or spherical form in the same way as in the operation on the flat bar. This done, the bar is removed and reheated, and laid in the flattening-die, figs. 10 and 11, and the male die, figs. 9 and 11, brought down upon the sphere or head, and it is flattened out into a disk-form, the projections a a, on the faces of the dies, forcing the metal from the centre, where the eye is to be, and driving it out towards the circumference, and filling the dies completely, besides working and strengthening the metal around the eye, where great strain and wear come, and economizing metal, as it is transferred to another part of the eye-bolt by the bulb-dies, and not wasted, as is the case when the bolt-hole is drilled, bored, or punched.

When it is desired to enlarge the end of a bolt, so that the proper thread cut upon it will not, at the bottom of the thread, be less in diameter than the body of the bolt, I prepare a pair of dies, one end of which grasps the bolt firmly, while the other is enlarged to the size of the exterior diameter that the thread should have. A plunger fits the die snugly, and when the bar is heated to a welding-heat, placed, and seized in the dies, the plunger is brought down or driven in, and the end of the bar is swelled out to the size required for such screw-thread.

Having thus fully described my invention, and shown how the same is accomplished, what I claim therein as new, and desire to secure by Letters Patent, is—

In making weldless links, and other similar articles, subjecting the previously swelled-up or enlarged end of the bar to the flattening and bulb-dies, substantially such as described, for the purpose of transposing the metal from the place where the bolt-hole is to be, and driving it towards the perimeter, as and for the purpose herein set forth.

GEO. H. SELLERS.
